UNITED STATES PATENT OFFICE.

CLINTON E. WILDER, OF IRVINE, PENNSYLVANIA.

METALLIC RAILWAY-TIE.

1,329,648.

Specification of Letters Patent.

Patented Feb. 3, 1920.

Application filed June 2, 1919. Serial No. 301,217.

To all whom it may concern:

Be it known that I, CLINTON E. WILDER, a citizen of the United States, residing at Irvine, in the county of Warren and State 5 of Pennsylvania, have invented certain new and useful Improvements in Metallic Railway-Ties; and I do hereby declare the following to be a full, clear, and exact description of the invention, such as will enable 10 others skilled in the art to which it appertains to make and use the same, reference being had to the accompanying drawings, and to the letters of reference marked thereon, forming part of this specification.

15 My invention relates to metallic ties for railways: the object thereof being to provide a metallic tie having resilient properties and which can be rolled from a single piece of metal.

20 The features of my invention are herein-after fully explained and pointed out and are illustrated in the accompanying drawings in which:—

Figure 1, is a side elevation of a blank 25 suitable for being formed into a tie according to my invention.

Fig. 2, is an end elevation thereof.

Fig. 3, is a side elevation of my improved metallic railway tie.

30 Fig. 4, is an end elevation thereof.

Fig. 5, is a plan view thereof.

Fig. 6, is a section on the line 6—6 in Fig. 5 on an enlarged scale showing the manner 35 of fastening a railway rail to said tie.

Fig. 7, is a T-bolt adapted for use as shown in Fig. 6.

In these drawings A indicates the base-plate of my improved metallic tie. Projecting upwardly from the central portion of 40 the base-plate A is a web A' as shown in Fig. 1. This is preferably formed by the rolling process as practised in the manufacture of structural steel.

In producing my improved tie I take a 45 piece of steel of the cross section, as shown in Fig. 2, of suitable length for a railway tie, and cut out the middle portion of the web A' as shown at B in Figs. 1, 3 and 5, thereby dividing the metal of the web A' 50 into the portions A² and A³. I also punch elongated openings a in suitable positions in said web A to receive bolts with which railway rails may be fastened to the ties as hereinafter described.

55 In forming the elongated holes a I preferably cause ears a' to be formed at the ends

of said elongated holes a on the under surface thereof adapted to engage heads of rail fastening bolts to prevent rotation thereof in said holes a. This blank shown in Fig. 1 60 is then placed in a suitable press and a portion A² of the web A' receives a longitudinal U-shaped bend, and the portion A³ of said web likewise receives an opposite U-shaped bend, as shown in Figs. 3, 4 and 5, the portions of said web having the elongated slots a therethrough forming the flat upper surface of the tie. It will be seen from the foregoing description, and the illustrations in Figs. 3, 4 and 5, that a tie formed according to my invention can be cheaply 65 manufactured; that it will have a limited degree of resilience, and that the elongated holes a will permit the railway rails secured to said tie to expand and contract without 70 distorting or injuring the tie.

In Fig. 6 I illustrate means for securing a railway rail C to a metallic tie formed according to my invention, in which D indicates a bolt having a T-head d which is 80 adapted to pass through the elongated opening a and engage the projections a' on the underside of the tie which prevent the bolt D from turning when the nut D' is being placed thereon. E indicates metal clamps 85 which are placed upon the bolts D and which overlap the base flange of the railway rail C for the purpose of clamping the same to the portions A² and A³ of my improved tie, the slots a permitting some movement 90 of the bolts D therein, thus permitting slight longitudinal movement of the rail C with relation to the tie to allow for expansion and contraction of the rail C.

Having thus shown and described my invention so as to enable others to utilize the same, what I claim as new and desire to secure by Letters Patent, is:—

1. In a metallic railway tie, a base plate, an upright plate at right angles to said base 100, and provided with a central opening therein, a U-shaped bend in one direction at one side of said opening, and a like U-shaped bend in the opposite direction at the opposite side of said opening, the upper faces of said 105 bends being substantially flat and parallel with said base, substantially as set forth.

2. In a metallic railway tie, a base plate, an upright plate at right angles to said base, and provided with a central opening therein, 110 a U-shaped bend in one direction at one side of said opening, and a like U-shaped bend

in the opposite direction at the opposite side of said opening, the upper faces of said bends being substantially flat and parallel with said base, and provided adjacent to the ends of said surfaces with transverse elongated slots therethrough to receive bolts, substantially as set forth.

3. In a metallic tie, the combination of a base-plate, a longitudinal web at right angles 10 to said base-plate, said web having the central portion thereof cut away, a right-hand longitudinal U-shaped bend in one end of said web, and a like left-hand bend in the

opposite end of said web, substantially as set forth.

4. In a metallic tie, the combination of a base-plate, a central longitudinal web at right angles to said base-plate, the plane of the upper portion of said web being parallel with the plane of said base-plate, elongated bolt receiving openings in said upper portion, and means to prevent a bolt from rotating in said elongated openings, substantially as set forth.

In testimony whereof I affix my signature. 25
CLINTON E. WILDER.
